UNITED STATES PATENT OFFICE

2,687,530

PETTICOAT OR THE LIKE HAVING BUILT-IN
HEM ADJUSTER

Alice M. Farnum, Kansas City, Mo.

Application May 21, 1951, Serial No. 227,447

1 Claim. (Cl. 2-217)

1 This invention relates to the manufacture of wearing apparel and particularly to a combination that includes a skirt-like garment, together with means for adjusting the lowermost edge thereof.

The invention hereof has to do most particularly with ladies' slips, petticoats or like undergarments wherein an aggravating problem is presented relative to maintaining the lowermost edge or hem thereof even and particularly at such height as to be normally obscured from view by the outer garments. The problem has become enhanced since introduction of the half slip.

Accordingly, it is the most important object of the present invention to provide a number of assemblies on a skirt-like garment, each of which is individually adaptable for raising or lowering the hemline adjacent thereto by merely shortening or lengthening certain tying elements forming a part of the assemblies.

It is another important object of this invention to provide an adjusting assembly for skirt-like garments that includes a strip of fabric or other flexible material secured directly to the garment in such manner as to present a pair of side-by-side tubes, the tying elements aforementioned, being within the tubes.

Another object hereof is to present an adjusting means that includes a single length of tying tape within the tubes of each assembly respectively and having its bight so disposed as to impart a lifting action to the hem when the ends of the tape are tied, all by means of formation of pleats or ruffles in the skirt itself and in the material forming the tubular portions of the assemblies.

Additional objects include details of construction, all of which will be made clear or become apparent as the following specification progresses, reference being had to the accompanying drawing, wherein:

Figure 1 is an elevational view of a petticoat or the like having a built-in hem adjuster made pursuant to my present invention.

Fig. 2 is an elevational view of one of the adjusting assemblies showing the tape untied.

Fig. 3 is an enlarged, elevational view similar to Fig. 2 but showing the tapes tied and one assembly in a hemline raising condition; and

Fig. 4 is a fragmentary, detailed, cross-sectional view taken on line IV-IV of Fig. 2.

A skirt-like garment in the nature of a half slip is illustrated in Fig. 1 of the drawing and broadly designated by the numeral 10. While the adjusting means of the present invention is

particularly adapted for use with this type of under-garment, it is to be understood that its application is not so restricted and may be well used for various other types of similar garments.

5 It is common practice to provide a continuous hem 12 at the lowermost peripheral edge of the petticoat 10 and the raising or lowering of such hem 12 is the primary feature of the present invention and function of a plurality of assemblies 14 mounted directly on the conventional garment 10. Each assembly 14, of which there are a plurality as desired, includes an elongated strip of material 16 that is flexible and preferably made from a fabric, although it is contemplated that lace might well be used for purposes of appearance in the same manner as is normally provided adjacent the hemline 12. The elongated strips of material 16 are secured directly to one face of the skirt 10 by means of three parallel, spaced-apart lines of stitching 18, 20 and 22 that are substantially perpendicular to the lowermost edge or hemline 12 of the skirt 10. These lines of stitching 18, 20 and 22 present a pair of side-by-side tubes or pockets 24 and 26 that are open 20 at the uppermost ends thereof and adapted to receive a tying tape 28.

25 Tape 28 is threaded in the uppermost end of tube 24 or 26 and at the lowermost ends of the tube, is threaded upwardly through the other tube to dispose the bight of the tape 28 in looped relationship to the lowermost end of the centermost line of stitching 20. The tape 28 need not be attached to the garment 10 or the material 16, but it is to be preferred that the aforementioned bight be also stitched to the garment 10 and/or the strip 16.

30 Another manner of constructing the assemblies 14 is to provide a pair of separate tapes, one for each tube 24-26 respectively, each having its lowermost end secured to the garment 10 by stitching or other fastening means.

In use, when it is desired to adjust the hemline 12 so far as height is concerned, either one or 45 all of the assemblies 14 may be placed in use and by pulling upon the ends of tape 28 projecting above the upper ends of tubes 24 and 26, the material forming the skirt 10 adjacent the tubes 24 and 26, as well as the material 16, will be gathered into Shirring or folds such as illustrated in Fig. 3 of the drawing and designated by the numerals 30 and 32 respectively. The tape ends are thereupon tied into a bow 34.

50 It is apparent that the assemblies hereof may be placed in use as desired and the extent to which the hemline 12 is shifted can be varied at

differing points therealong and it is further obvious that the use and attachment of the assemblies 14 to a garment of this character will not detract from its appearance or provide for any discomfort on the part of the wearer.

Having thus described the invention what is claimed as new and desired to be secured by Letters Patent is:

In a woman's undergarment, a fabric skirt having a body portion adapted to extend from the waistline downwardly and provided with a free lowermost edge; and a number of spaced, identical assemblies extending upwardly from said lowermost edge of the body for adjusting the height of said lowermost edge each assembly comprising a single elongated strip of fabric, three spaced, vertical lines of stitching securing said strip to the body on the outermost face thereof, presenting a pair of elongated, vertical, side-by-side

tubes having the uppermost and lowermost ends thereof open, and an elongated, single length of fabric tape in the tubes and looped beneath the centermost line of stitching, said tape extending beyond the tubes at the uppermost end of said centermost line of stitching, presenting a pair of tying ends normally tied in a bow on said outermost face of the body well below said waistline thereof and across the centermost line of stitching with said strip Shirred.
